Technical drawing of a mechanical assembly, likely a valve or pump component, labeled Fig. 23. The drawing shows a complex arrangement of parts, including a central circular assembly with various internal features and a surrounding housing. Numerous parts are labeled with reference numbers, such as 119, 120, 118, 99, 230, 231, 233, 252, 116, 214, 123, 112, 117, 113, 109, 108, 107, 212, 211, 104, 103, 102, 173, 172, 103, 100, 171, 101, 108, 109, 110, 106, 174, 220, 230, 105, 224, 224, 222, 221, 225, 223, 68, and 214. The drawing uses lines, circles, and hatching to represent different materials and features like springs and holes.

CALCULATING MACHINE CONDITIONABLE FOR AUTOMATIC MULTIPLYING, ESPE- CIALL SHORT-CUT MULTIPLYING

John Lydfors, Kopenhamnsvagen 11A, Malmo, Sweden

Filed Nov. 28, 1955, Ser. No. 549,473

Claims priority, application Sweden Dec. 3, 1954

5 Claims. (Cl. 235—60)

This invention relates to a calculating machine that may be conditioned for automatic multiplying and particularly a machine for short cut multiplication.

One of the objects of my invention is to provide an improved multiplying device capable of being combined with a calculating machine of conventional design, and also those machines which are provided with a printing device.

Further objects of the invention will appear from the description and claims.

In the drawings in which and embodiment of my invention is shown:

FIGURE 1 is a plan view of the machine;

FIGURE 2 is an enlarged plan view of the key board mechanism of the multiplying device;

FIGURE 3 is a partial vertical section taken on the line 3—3 of FIGURE 2, showing the key for the digit "1";

FIGURE 4 is a partial vertical section taken on the line 4—4 of FIGURE 2, showing the key for the digit "7";

FIGURE 5 is a side view of transmission elements for registering the character of the digits introduced;

FIGURE 6 is the appertaining plan view;

FIGURE 7 is a side view of a registering mechanism;

FIGURE 8 is the appertaining plan view;

FIGURES 9 and 10 show in side view and plan view, respectively, a bow device associated with the registering mechanism;

FIGURE 11 shows a mechanism for the selection of positive and negative feeding;

FIGURE 12 is the appertaining plan view;

FIGURE 13 shows in side view parts of a mechanism for starting and stopping the machine;

FIGURE 14 shows the same mechanism in plan view;

FIGURE 15 shows in side view additional parts of the last-mentioned mechanism;

FIGURE 16 is the appertaining plan view;

FIGURE 17 shows in side view members for the selection of positive or negative feeding;

FIGURE 18 is the appertaining plan view;

FIGURE 19 is a side view of members for obtaining an additional entry impulse;

FIGURE 20 is the appertaining plan view;

FIGURE 21 shows in side view an axle clutch;

FIGURE 22 is a plan view of the same member;

FIGURE 23 is a side view of the driving arm system of the machine;

FIGURE 24 shows in side view a controlling arm system;

FIGURE 25 is a plan view of the driving lever system and the controlling arm system;

FIGURE 26 shows in side view a detail cooperating with the mechanism illustrated in FIGURE 17;

FIGURE 27 is the appertaining plan view;

FIGURES 28 and 29 show a side elevation of the complete multiplication unit and FIGURES 30 and 31 show top plan views of the arrangement as shown in FIGURES 28 and 29, respectively.

The calculating machine may be fitted with any described actuator, such as a pin wheel drum (Odhner wheel drum) or a setting carriage, and be provided with a normal key board for addition, such as a ten-key keyboard or a full key board.

According to a selected embodiment, the multiplying

2

device according to the invention is built as a unit which is mounted at one side of the calculating machine and fitted with an individual key board for introducing the multiplier. The adding machine may be a machine provided with a totalizer, and means to enter amounts into the totalizer, as shown for example in U.S. Patent No. 2,397,745 issued April 2, 1946 to Karl B. W. Kiel.

The accompanying drawings illustrate an example of a machine according to the invention, in which example the main driving shaft of the multiplication device is arranged to carry out an oscillating rotary motion. However, the invention is not limited to such an oscillating motion. The main driving shaft may, within the scope of the invention, be always rotated in the same direction, and guiding curves or eccentrics being operative in cases where a stroke movement or an oscillating movement is desirable.

In FIGURE 1 is shown a printing calculating machine 1 of conventional type associated with the multiplying device 2 according to the invention. The machine 1 may be an adding and subtracting machine provided with a bank 3 of depressible amount keys, an actuator or setting device and a totalizer (not shown), window openings 4 and 5 for reading off the amounts of the actuator and of the totalizer, printing members 6 for printing the result of the calculating operation and a printing device 7 for printing the multiplier.

The multiplying device 2 is mounted along the right side of the adding machine and is provided with a key 8 adapted to start the printing control mechanism and a key board comprising ten multiplication keys 10. The keys are arranged in two columns located side by side, with one column containing the keys for the digits "0," "2," "4," "6," "8" and the other column the digits "1," "3," "5," "7" and "9."

The multiplication keys are each provided with a stem guided for movement in the vertical direction. According to example shown, the key 10 for the digit "1" is shown in a side view in FIGURE 3. The stem 11 of the key, guided in known manner in the lateral direction, is formed with two guide slots 12 and 13 parallel to each other, which are adjustable on fixed horizontal rods 14 and 15, respectively. In this way, the stem 11 may be adjusted in its axial direction downwards against the action of a spring 16. The stem 11 is provided with a pin 17 engaged with a slot 18 in a lever 19, which last-mentioned component is swingable in the vertical plane on a horizontal axle 20. The slot 18 extends in the longitudinal direction of the lever 19 so that the pin 17 travels, during the depression of the key 10, along the slot 18.

The lever 19 is integral with a multi-slotted guide plate 21 formed with the three different guide slots 22, 23 and 24. Said guide slots, each of which is arranged to operate with a corresponding movable member and which are adapted, upon the depression of the key, to displace or fix the position of said movable member, and each has a separate task. Thus, the guide slot 22 has for its purpose to indicate the digital value representing the properties of a group digits. The digit series is divided into two groups, with a first group containing the digits "0" to "5" and a second group containing the digits "6" to "9." In the shown example, in which the guide plate 21 is adjustable by means of the key for the digit "1," the guide slot 22 is designed for entry of said digit as a positive one. The movable member controlled by the guide slot 22 consists of a horizontal rod 25 forming part of a swingable bow mounted in the frame of the machine. The rod 25, which is common to all of the slotted disks, is located as shown in FIGURE 3 in the position corresponding to the digit "0." However, it may be displaced in steps, to the left according to the figure, into five different positions corresponding to the

digits "1" to "5." The center lines for the zero position as well as for the five other positions are marked by dashes. The lower part of the guide slot 22 is formed with a width corresponding to the diameter of the rod 25 and follows an arc line concentric with the mounting axle 20 of the lever 19 and is located a radial distance from said axle corresponding to the value represented by the appertaining figure key, i.e. in the present case the digit "1." The upper part of the guide slot 22 has such a width that the rod 25 may be moved by anyone of the guiding disks into its representative positions. Thus, the rod is shown in FIGURE 3 in an initial position, the zero position, from which upon the depression of the key 10, it is displaced one step to the left when the lower part of the guide slot passes into engagement with the rod. The value-determining part of the edges of the guide slot 22 consists of an arc shaped portion 26 which at the top is joined to an edge portion 27 at a greater radial distance than the edge portion 26. Thus, the edge portion 26 of the different guide slots lies at different radial distances from the axle 20 of the slotted plates, the shortest radial distance thus corresponding to the digit "5." At its end portions, the rod 25 is rigidly connected to two arms swingably mounted on a horizontal axle 29, and one arm 30 (FIGURE 5) of which transmits the guided motion of the rod 25.

The second guide slot 23 (FIGURE 3) has for its purpose to select the sign for the operation, i.e. to indicate positive or negative feeding. The upper portion of the guide slot 23 encloses a rod 31, which is displaceable parallel to a position 32, marked by dot and dash lines, to the right of the initial position shown. When the rod is in the initial position, the machine is occupied with positive feeding, whereas upon the displacement of the rod 31 into the position 32 negative feeding takes place. The lower portion of the guide slot 23 is so designed that during the depression of the key 10 for the digits "1" to "5" the rod 31 is maintained in the position corresponding to positive feeding. If, accidentally, the rod should occupy the position designated by 32, it will be returned to the position corresponding to positive calculation. By means of two arms, the rod 31 is swingable about a horizontal axle 33 situated adjacent and a short distance in front of the axle 29.

The third guide slot 24 (FIGURE 3) serves to start and to stop the machine, and the upper portion of the guide slot has a greater width than the lower and encloses a rod 34, which is displaceable in parallel from the shown position into a position 35, marked by dot and dash lines, to the right of the shown initial position. When the rod 34 moves to the right into the position 35, the machine is started. The lower portion of the guide slot 24 is so formed that the rod 34 is moved from the initial position into the starting position when the key 10 is depressed. The rod 34 is swingable about a horizontal axle 36 situated above the slotted disk 21. The axle 36 is parallel to the above-mentioned axles 29 and 33 for the rod 25 and 31, respectively.

In order to localize the different mechanisms belonging to the multiplying device vertical mounting walls A, B, C and D have been marked in the plan views with dot and dash lines. The walls extend in the longitudinal direction of the machine and are parallel with the right hand side wall of the calculating machine 1.

The rod 25 intended for indicating the digit value is fastened, at one end, in the lever 30 (FIGURE 5), which is forked. One shank 38 of the lever serves as an abutment for a pin 39, whereas the other shank 40 constitutes an attachment for a spring 41 connected to said pin 39. The lever 30 is swingable about the axle 29 and is shifted directly by means of the guide slot 26 upon the depression of the key 10.

Said pin 39 is fixed in a curved lever 42 (FIGURE 5) which is mounted freely on the horizontal axle 29. Thus, the arm 42 is brought to participate in the movement of

the forked arm 30 under the influence of the spring 41. In this way, the lever 42 is normally displaced the same angle as the rod 25. The outer part of the lever 42 is provided with a link 43 which, at 44, is articulated to the lever 42. At its free end, the link 43 is provided with a pin 45 arranged to be inserted in one or the other of five recesses 46, 47 placed in a series, after the lever 42 has been angularly displaced from the shown position into a certain given position dependent on the value of the depressed key 10. In the normal position, the pin 45 is located immediately before the recess 46 corresponding to the digit "0." Then there follow, in a row upwardly, four recesses 47 separated from each other by means of cog like portions 48. Said recesses thus correspond to the digits "1," "2," "3" and "4." For the digit "5" the pin 45 is inserted at the upper side of the uppermost tooth 48 at a place designated by 49. The cogs 48 form parts of a member 50 which in the following description is termed "comb."

As appears from FIGURE 7, the comb 50 constitutes the outer portion of a lever 51 swingably mounted on the axle 29, which lever 51 in the following description is termed "registering lever." The tooth-gap like recesses 46, 47, 49 are situated along an arc concentric with the axle 29. In FIGURE 5 the lever 42 is shown, by means of dot and dash lines, in a raised position, in which position the pin 45 is located immediately in front of a recess 47 corresponding to the digit "2." Correspondingly, the rod 25 is shown, by means of dot and dash lines, in a position designated by 53 and corresponding to the same digit. By means of full lines, the rod 25 is shown in the position corresponding to the digit "0." Similarly, the forked lever 38, 40 is shown, by means of dot and dash lines, in a position 54 corresponding to the position 53 of the rod. Further, it appears from FIGURE 5, that when the rod 25 has been shifted from the zero position to the position corresponding to the digit "2," the lever 42 has been entrained by the spring 41 so that the pin 39 on the last-mentioned lever always rests against the shank 38, which results in the pin 45 being moved upwardly from the shown initial position into the position corresponding to the digit "2."

The introduction of the pin 45 into engagement with the comb 50 is effected by the aid of a bow 55 (FIGURES 9, 10), which is swingable about a horizontal axle 56. The bow is formed with a substantially triangular recess 57, both opposite longitudinal edges 58 and 59 of which follow arcs, which have a radius corresponding to the distance from the axle 29. In the shown position, the upper edge 59 of the recess determines the path, along which the pin 45 travels upon the movement of the lever 42. The bow 55 is swingable from the shown position in a clockwise direction so that the lower edge 58 of the recess moves into engagement with the pin 45 and pushes this latter into one of the tooth gaps of the comb 50. As a consequence, the edge 58 of the recess 57 when the pin is in the broken line position of FIGURE 9, will occupy approximately the same position as the edge portion 59.

As shown in FIGURE 7 the comb 50 is joined with a toothed sector 60 having six teeth 61 extending upwardly. The toothed sector 60 is integral with the registering arm 51 and is situated at a shorter radial distance from the axle 29 than the comb 50. The toothed sector and the comb are provided with a corresponding pitch. Moreover the registering arm 51 has a curved recess 62, and one edge portion of which is formed with teeth 63 for the purpose of positioning the arm 51 by the aid of a spring loaded peg 64 cooperating with said tooth series 63. The toothed sector 60 is driven by means of a pin wheel 65 provided with a single tooth 66, which pin wheel is always rotatable in a clockwise direction by means of a motor driven shaft 67. Thus, the pin wheel is arranged to displace the toothed sector 60 one step upwardly for each complete rotation, whereby the registering arm 51, after

having been swung downwards from the shown initial position, may be returned thereto. In FIGURE 7 there is shown, by means of dot and dash lines, a position of the arm 51 resulting from a downward movement corresponding to two pitch steps of the comb 50. Such a movement takes place when the key for the digit "2" is depressed and the driving mechanism is started.

The Driving Arm System

The driving mechanism contains a driving arm system, the functions of which will be more closely described in connection with FIGURE 23. Said driving arm system is swingable about its axis to and fro through an angle of about 60°. During this stroke of 60°, the arm system passes into engagement with a pin 68 provided at the outer part of the same lever 42 (FIGURES 5 and 6) as carries the link 43 with the pin 45. The lever 42, which in this case is coupled to the registering lever 51 by means of the pin 45, is swung downwardly so that a number of teeth 61 of the sector 60 corresponding to the registered digit have moved downwardly past the pin wheel 65. When this wheel is started, the sector 60 with the comb 50 steps back to the shown initial position. The number of revolutions of the pin wheel shaft 67 determines the number of additions or subtractions in the calculating machine 1 in correspondence to the input digit value. In connection with the above it should be stated that the lever 42 may be angularly adjusted in the clockwise direction independently of the lever 30 against the action of the spring 41. This occurs upon the stroke of the driving arm system. On the other hand, the lever 42 is adjusted after the return of the bow 55 to its initial position and hence after the release of the pin 45 from the comb 50, into the initial position by the aid of the forked arm 30, which last-mentioned arm is guided by the aid of the key 10 and the appertaining slotted guide disk 21.

The rod 34 adjustable by means of the guide slot 24 is swingably mounted on the axle 36 by means of two mutually parallel arms. One of said arms is designated by 69 and, as shown in FIGURE 13, is integral with an arm 70 and an arm 71, which latter arm carries an abutting edge 72 and an angle arm 73 connected to one end of a horizontal rod 74, the other end of which is fixed in a lever mounted on the axle 36. The arm 70 passes obliquely upwards from the mounting axle 36 and is formed, at its end portion, with a nose 75 intended to cooperate with a pin on a circuit closing arm described below in connection with FIGURES 13 and 15.

FIGURES 21 and 22 show an axle clutch of the kind described in my prior Patent No. 2,654,455, dated October 6, 1953. A disk 77 provided with an actuating pin 76 is rotatable about a horizontal axle pin 78. The pin 76 engages with a Z-shaped guide slot 79 in a coupling lever 80 swingable about an axle 81. The guide slot 79 is so formed that upon turning of the lever 80 in a counterclockwise direction about the axle 81, the pin 76 moves into engagement with the lower part of the guide slot 79, whereby the disk 77 turns in a counterclockwise direction approximately one eighth revolution. A fixed guide flange 82 and a guide flange 83 provided on the disk 77 are arranged to adjust angularly a rocker arm 84 carried by a rotatable disk 85. The rocker arm 84 is shown in operative position in FIGURE 21. Upon the withdrawal of the guide flange 83, the rocker arm 84 is moved into said operative position from an inoperative position shown in FIGURE 22.

The lever 80 containing the guide slot 79 is actuated by a spring 86, which tends to turn the lever 80 in a counterclockwise direction. A frame wall 87 carries the guide flange 82 and is formed with a circular opening, in which the disk 85 is rotatable so that the rocker arm is located in its operative position, on the front side of said wall, as shown in FIGURE 21. A branch arm 88 on the coupling lever 80 is directed downwardly, and at its outer end is provided with a stop pin 89 and, at

a certain distance therefrom with an abutting pin 90 (FIGURE 21). The last-mentioned pin is adapted to rest against a cam disk 91, rigidly secured to the disk 85, so that the coupling lever 80 is retained by the cam disk 5 in its inoperative position during the greater part of the revolution of the disk 91. However, during the remaining part of the revolution the coupling lever 80 may, in case the stop pin 89 is freed, be brought into an operative position, i.e. be turned in a counterclockwise direction about its axle 81.

It appears from FIGURE 13 that the stop pin 89 is controlled by a locking lever 92, which is mounted on a shaft 93 and is provided with a branch arm 94 extending downwardly, and actuated by a spring 95, which tends to maintain the locking lever in engagement with the stop pin 89. The locking lever 92 is arranged to be moved into the position, in which the pin 89 will be freed, by the lever 71 connected to the starting rod 34, the abutting edge 72 of said lever 71 connected to the starting rod 34, the abutting edge 72 of said lever 71 passing into engagement with a pin 96 on the branch arm 94 during the travel of the rod 34 to the position of starting.

When the rocker 84 is brought into its operative position it will engage a rotatable disk which represents the 25 driven part of the axle clutch as hereinafter will be more fully described.

The keys 10 for the digits "0" to "5" are coupled to their slotted guide disks 21 substantially in the same manner as the key "1" according to FIGURE 3, i.e. 30 the stem of the keys passes into engagement with the lever 19 to the left of the shaft 20 of said lever 19 so that the slotted disk 21 is swung upwards upon the depression of the key. On the other hand, the keys 10 for the digits "6" to "9" are coupled to the slotted guide disks 21' in such a manner that said disk, upon the depression of the key, are swung downwardly about the axle 20. In FIGURE 4, the key 10 for the digit "7" is shown as coupled to its guide disk 21'. By means of vertical slots 12' and 13', the key stem is guided on 40 horizontal rods 14' and 15' in conformity to the key stem 11 for the key "1." A pin 97 is fastened to the key stem and arranged in engagement with a slot 98 in the slotted guide disk and actuated by a spring 99, which tends to move the pin and hence the key and the slotted disk upwardly. The disks 21' are formed with guide slots 22', 23' and 24' corresponding to guide slots 22 to 24 according to FIGURE 3 and so designed that the rods 25, 31 and 34 are moved in the desired manner. Upon the depression of the key, the guide slot 22' displaces the rod 25 a number of steps corresponding to the 9's complementary value of the digit of the key. The guide slot 23' displaces the rod 31 to the negative position, and the guide slot 24' displaces the starting rod 34 to its position of starting upon the depression of the key, in the same manner as the guide slot 24 according to FIGURE 3.

More particularly, by depressing one of the multiplication keys 10, the machine starts by virtue of the guide slot 24 adjusting the rod 34. At this moment, the shaft 67 starts to rotate in a clockwise direction and thus steps 60 the lever 51 back to zero. When this zero position has been attained, the toothed sector 60 has been moved out of engagement with the tooth 66 on the wheel 65. If the machine still is running, the lever is maintained unactuated in the zero position.

The operating members of the multiplication device are, according to the selected example, driven by a driving arm system 100 actuated by a spring 99, as shown in FIGURE 23, which system by means of a cam disk or guide slot device, is provided with an oscillating stroke motion about its axle 101 through an angle of approximately 60° to and fro. The driving arm system is driven by the aid of the axle clutch 84, 85 described in connection with FIGURES 21 and 22.

The driving arm system according to FIGURES 23

and 25 contains four arms, namely an arm 102 extending upwardly, an arm 103 extending obliquely upwards to the right side, an arm 104 directed obliquely downwards to the right, and an arm 105 directed to the left. This latter arm is arranged to move, in a normal case, i.e. when no additional entry impulse is required, the pin 68 downwardly together with the arms 42 and 51, as stated in connection with FIGURES 5 and 7, so that the comb 50 and the sector 60 are moved downwardly into the initial position of the arm 42.

The lever 102 is provided with a curved arm 106 coaxial with the axle 101. Also the arm 104 has a similar curved arm 107, which curved arms extend toward each other in a peripheral direction. In the arms 104 and 105 there are two mutually parallel slots 108 constituting guide slots for two pins 109 fixed in a slide 110 (FIGURES 19 and 23). Thus, this latter is displaceable in its longitudinal direction on the arm system 100. For the purpose of retaining the slide in one extreme position or the other, which is determined by the length of the slots 108, there is provided in an adjacent frame part of the machine an M-shaped recess consisting of two arc-formed guide slots 111 and 112 coaxial with the axle 101, said guide slots being at the lower ends joined to each other in such a manner that a guide pin 113 fastened to the slide is freely displaceable in the recess throughout the length of stroke of the slide 110. The curved guide slots 111 and 112 are located at a radial distance from each other corresponding to the length of stroke of the slide so that through the displacement of the slide the guide pin 113 may be set either under the mouth of the slot 111 or under the mouth of the slot 112, which last-mentioned position is shown in the FIGURE 23. The slide 110 serves to carry out an additional entry impulse in the machine, and for this purpose the slide 110 must be displaced from the right extreme position shown to the left extreme position marked by means of dot and dash lines (FIGURE 19). This displacement is effected by the aid of an arm 116, which is adapted to engage a pin 117 disposed on the slide a small distance above the guide pin 113 and directed in a direction opposite to this pin. The arm 116 is turned in a clockwise direction about an axle 118 under the action of a spring 119 interposed between the arm and a fixed pin 120. As shown in FIGURE 19 the arm 116 is locked by a pawl 121 swingable about a pin 122. Said pawl cooperates with a pin 123 on the lower part of the arm 116. The pawl 121 is actuated by a spring 124, which tends to turn the pawl member into engagement with the pin 123. Thus, by turning the pawl 121 out of engagement, the arm 116 is freed, whereby the arm exerts a pressure on the pin 117 under the influence of the spring 119 so that the slide is displaced from the shown position into its left extreme position intended for the entry of the multiplicand additionally into the totalizer of the adding machine.

The adjustment of the pawl 121 to freeing position takes place by the aid of an arm 125 appertaining to an arm system 126, shown in FIGURES 24 and 25, which is freely mounted on the axle 101. The movement of the arm system 126 will be more specifically described in connection with FIGURE 24. The left end portion 114 of the slide 110 occupies, in the operative position of the slide, such a position in relation to the arm 105 that the pin 68 on the arm 42 is brought downwards upon the stroke motion of the driving arm system one pitch step below the zero position corresponding to the pitch of the comb 50, whereby the pin wheel 67 must perform an additional rotation in relation to the digit value registered by the arm 51, and the multiplicand is entered a further time into the totalizer. As a rule, it may be stated that the slide 110 is displaced into operative position every time a change of sign, plus or minus, takes place for the calculating operation.

The arm 116 shifting the slide is provided with a pin 75

127, on which an arm 128 is swingably mounted. The two arms 116 and 128 are interconnected by means of a spring 129 in such a manner that the arm 128 is moved in a counterclockwise direction when the arm 116 is turned in the same direction. As a result, the arm 128 passes into engagement with the pin 117 on the slide and brings this latter part to the initial position.

The change of sign in the calculating operation is indicated, as mentioned above, by the rod 31 when this 10 later part is displaced from the positive to the negative position, or vice versa. The mechanism for obtaining the additional entry is described below with reference to FIGURES 17 and 18. By means of mutually parallel arms the rod 31 is swingable about the axle 33. One of 15 these arms is shown in the drawing and is designated by 130. The arm 130 is shown in full lines in the position corresponding to positive setting-up. A spring 131 tends to turn the arm in a counterclockwise direction. At the upper part of the arm there are provided two pins 132 and 133 constituting supporting pins for each of the shanks 134 and 135, respectively, of a spring 136 so bent as to have the shape of a hair pin, and with said spring 20 grasping, by means of an eye 137, a pin 138 on the arm 130. The two spring shanks 134, 135 extend upwardly 25 beyond the arm 130 and each rest against corresponding pin 139 and 140, respectively, on a branch arm 141 appertaining to an arm 142 likewise swingable about the axle 33. The branch arm 141 constitutes substantially a bow concentric with said axle 33. From the upper part of 30 the arm 130 there extends an angle lever 143, which is provided with a pin 144 arranged in engagement with a slot 145 in a lever 146. This latter is swingable about an axle 147. The lower part of the lever 146 is curved and arranged to cooperate with a rocking lever 148, which 35 last-mentioned lever is swingable about a pin 149 and is actuated by a spring 150 which tends to turn the rocking lever in a clockwise direction. The rocking lever is provided with a pin 151, with which the lever 146 passes into engagement for the purpose of angularly adjusting 40 the rocking lever against the action of the spring 150 into a position shown by means of dot and dash lines. This takes place when the rod 31 is displaced from the positive to the negative position, i.e. from the left position shown to the position marked by 32 in FIGURE 3. During said adjustment, the movement is transmitted by 45 means of the arm 130, 143 to the lever 146, which in turn adjusts the rocking lever in the manner stated above.

As shown in FIGURES 26 and 27, the rocking lever is mounted at one end of a lever 152, which is swingable about an axle 153 and the other end of which is formed with a slot 154 enclosing a pin 155. The lever 152 is turnable in a clockwise direction, and hence the rocking lever 148 will occupy a position above a pin 156 on the arm 142 (FIGURE 17). Thus, the rocking lever 148 is retained in its angular position relatively to the lever 152 by the aid of the spring 150, one end of which is connected to the rocking lever, and its other end being 50 united with the lever 152. However, when the arm 152 is moved downwardly back to the position shown by means of full lines, the outer edge portion 157 of the rocking lever passes into engagement with the pin 156, provided said pin is situated in the path of the rocking lever upon the downward movement of the lever 152.

The arms 130 and 142 (FIGURE 17) coupled together 55 by means of the hair-pin spring 136 are included in the mechanism which impels the additional entry of the adding machine. An angle lever 158 connected to the arm 142 is provided, at its outer end, with a pin 159 intended to pass into engagement with either of two 60 abutting edges 160 and 161 on the lower part of an up-standing arm portion 162 appertaining to the arm system 126 mounted on the axle 101 (FIGURE 24). The arm 162 is provided, at its upper end, with a pin 163 intended to cooperate with a pawl 164 swingable about a pin 70 165 and actuated by a spring 166, which latter spring

tends to move the pawl 164 into engagement with said pin 163. The hair pin spring 136 is comparatively weak so that the angle lever 158 can be moved in a clockwise direction such a distance that the pin 159 comes into contact with the edge portion 160 without any appreciable pressure being transmitted to the arm 162. For the displacement of this arm 162, moving force is taken from the driving arm system so that the work involved in the impulsing is relieved from the key 10. A pin 167 on the angle lever 158 is moved, upon the initiated movement of the rod 31 to the right, into the path of the curved arm 106 of the driving arm system 100. As stated above, said arm 106 is swingable in a counterclockwise direction through an angle of 60° during the working stroke. When the curved arm 106 engages the pin 167 on the angle lever 158, said angle lever is caused to swing in a clockwise direction about its axle 33, and the pin 159 passes into engagement with the edge portion 160 on the arm 162 and causes this latter arm to swing a short distance to the right so that the pin moves into locking engagement with the pawl 164. During this time, the pin 159 reaches a position immediately below the edge portion 161 on the arm 162. A branch arm 168 extending downwardly and connected to the arm 162 (FIGURE 24) forms, at its lower part, an abutting edge intended to engage the pin 96 on the arm 94 (FIGURE 13), which carries the locking arm 92. Thus, upon upward movement of the arm 168 the locking arm 92 is displaced upwardly so that the locking pin 89 is freed and the axle clutch may start.

As shown in FIGURE 24, the arms 162 and 168 constitute branch arms of the arm system 126, which is a control arm system and contains the above-mentioned arm 125 as well as an arm 170 extending downwardly. The last-mentioned arm is combined with a mechanism containing a tabulating dent (not shown). The tabulating detent is brought to operative position upon the rotation of the arm system 126 as a clockwise direction in consequence of the action of the impulse arms 142.

The stroke of the driving arm system 100 is obtained by the aid of a pin 171 running in a guide slot 172 provided in a disk 173 (FIGURES 22 to 25). Said disk is rotatable about an axle 174 and constitutes the driven part of the axle clutch 84, 85, i.e. that part which is driven by the rocking lever 84 when this latter, according to FIGURE 21, is angularly adjusted to its operative position in which the lever 84 engages a lug 173'. In this instance, the disk 173 is driven one revolution in a counterclockwise direction.

Arm 125 of the arm system, by means of which the pawl 121 is moved into its inoperative position by means of a pin 176 provided, is connected by means of an upwardly directed spring 177 to the pin 120 and is formed with a slot 178 engaging a pin 179. Said pin is fastened in a rocking lever 180 (FIGURE 15) swingable about a pin 181 on the lower part of a locking arm 183 mounted at 182, which locking arm is arranged to pass into engagement with a pin 184 at the outer end of a branch arm 185 extending from a downwardly directed circuit closing lever 186, which is swingable about an axle 187. At its mid-portion, the circuit closing lever is provided with a pin 188 intended to be actuated by a guide cam 189 (FIGURE 11) arranged at its lower end to actuate a switch (not shown). The switch in question may be of the type shown in Patent No. 2,397,745 wherein the elements 471-472 cooperates with a cam disc 484 which disc in turn actuates a cam roller 488 on a lever 489 governing the main shaft 323 of the adding machine. The circuit closing lever 186 is also provided with an upwardly directed branch arm 192, which at its outer end carries a pin 193 (FIGURE 13). This pin is arranged to engage the nose 75 of the arm 70 by the aid of an abutting edge 194 provided at the outer end of said arm 70. Thus, when the rod 34 is moved, by the aid of the guide slot 24 in the guide disk of the key 10, from the left position shown to

the right position designated by 35, the arm system 70, 71 is swung in a counterclockwise direction about its axle 36, whereby the edge portion 194 at the upper end of the arm 70 raises the pin 93 provided on the arm 192 to the position shown by means of dot and dash lines, the circuit closing lever 186 thus being moved from the position, shown by full lines to the position shown by means of dot and dash lines, in which last named position the aforementioned switch is closed. Simultaneously, the branch arm 185 appertaining to the circuit closing lever is moved downwardly so that the pin 184 is engaged by the pawl 183 and is retained in the set position under the influence of a spring 195 connected to the pawl 183.

The adjustment of the rocking lever 180 and thus of the pawl 183 from the locking position shown by means of dot and dash lines takes place by the aid of disk 260 driven continuously and provided with an eccentric pin 201, and said disk being rigidly secured to a shaft 202 driven by the motor of the machine in a clockwise direction. When the branch arm 185 connected to the circuit closing arm 186 is displaced downwards to its lowest position and passes into locking engagement with the pawl 183, and the latter is turned through an angle in a clockwise direction about its axle 182. During the displacement of the pin 184 downwardly, the pawl 183 rests, by means of a straight guide edge 203 against said pin so that during said movement the pawl maintains its angular position against the action of the spring 195. When the pawl occupies its locking position, the rocking lever 180 is moved into the path of the eccentric pin 201. By this, the rocking lever is thrown back, together with the pawl 183 in a counterclockwise direction, which results in the pin 184 being freed and the motor circuit is opened.

In the driving arm system 100 above described (FIGURE 23) there is included the downwardly directed part 104 having the curved arm 107. This last-mentioned arm is formed with a curved guide slot 210 arranged coaxially with the axle 101 and joined to an angularly disposed part 211. This guide slot is for displacing a pin 212 approximately radially in an outward direction from the axle 101 into a position 213 shown by means of dot and dash lines. Said pin 212 is fastened in the outer part of the bow arm 55 (FIGURE 9), which is swingable about the axle 56 and intended to bring the pin 45 into engagement with the comb 50. This occurs when the arm system 100 is swung in a counterclockwise direction, and the pin 212 during the greater part of said oscillating motion being maintained in the position designated by 213. When the arm system has completed its oscillating motion in the counterclockwise direction, a shoulder 214 located on the curved arm 107 passes into engagement with a pin 215 on a slide mechanism controlling the tabulation of the machine, which mechanism is shown in FIGURE 11.

The other curved arm 106 of the driving arm system 100 is provided with a pin 220 which, upon the stroke of the arm system in a counterclockwise direction, actuates a latch 221. Said latch is swingable about a pin 222 and is actuated by a spring 223, which tends to turn the latch in a counterclockwise direction about the axle 222 so that the outer part of the latch rests against a pin 224 on the starting arm 70 (FIGURE 13). This arm also serves as a locking arm for the keys 10, since the same, due to their connection to the rod 34, maintain the key in the depressed position. When the pin 224 is in engagement with a recess 225 provided in the latch 221, the arm 70 is retained in the key locking position. By the aid of the pin 220 of the arm 102 the latch 221 is moved out of the engaging position, and the pin 224 is freed so that the arm 70 may return to the initial position. Simultaneously, the circuit closing lever (FIGURE 15) is permitted under the action of a spring 226 secured to the pin 188 to return into the circuit opening position. Thus, when the latch is swung into inoperative position, the arm system 70, 71 connected to the rod 34 (FIGURE 13) may return

to the initial position. If one of the keys 10 is maintained in the depressed position, the rod 34 is maintained in the starting position.

On the branch arm 103 of the driving arm system 100 there is provided a pin 230, which is arranged to raise the pawl 164 to a freeing position for the pin 163. The pin 230 is provided with a part 231 angularly disposed in relation to the arm 103, the outer edge portion of said part forming a guide cam 232 arranged upon the return stroke of the arm 103 to restore the slide-displacing arm 116 to the initial position and the guide cam 232 then passing into engagement with a pin 233 on the arm 116. By this, also the slide 110 is restored, which takes place by the aid of the arm 128 (FIGURE 19).

In the registering arm 51 there is secured outside the comb 50 a pin 240 (FIGURES 7 and 11), which during the setting movement of the arm 51 runs in a slot 241 provided in an arm 242. This latter arm is swingable about a pin 243 and is integral with the guide curve 189 mentioned in connection with the pin 188 of the circuit closing lever (FIGURE 15). Said guide curve forms the upper edge of a plate shaped part of the arm 242, the opposite edges of which form a guide curve 244 serving to cooperate with a pin 245 provided on a slide 256 displaceable in a horizontal direction. As shown in FIGURE 11, the slide has two guide slots 247 parallel to each other and engaged by pins 248. A spring 249 tends to move the slide 246 to the left so that the pin 245 of said slide rests against the guide curve 244. In the slide 246 there is fastened the pin 215, which is arranged for actuation by the lug 214 (FIGURE 23). By means of the pins 248 the slide is mounted on an arm 251 swingable about an axle 252 and actuated by a spring 253, which spring tends to swing the arm in a counterclockwise direction about the axle 252. When the lug 214 passes into engagement with the pin 215, this latter part is moved a certain distance upwardly and causes the slide 246 and the carrier of this slide, viz. the arm 251 (FIGURE 11), to perform a stroke constituting an impulse for tabulation. The lower part of the arm 251 is provided with a pin 254, which is engaged with a fork 255 appertaining to an arm 256 which transmits the tabulating impulse.

The arm 242 (FIGURE 11) having the guide cams 189, 244 and swingable about the axle 243 (FIGURE 7) has an upper portion 260 located above said axle and arranged to engage the detent pin 89 disposed at the lower part of the arm 88 of the arm 80 which controls the engagement and release of the axle clutch 85. When the arm part 260 is swung in a counterclockwise direction to the position shown by dot and dash lines in FIGURE 11, the adjustment of the axle clutch into operative position is impeded. A guide slot 261 on that part of the arm 242 which is located between the guide cams 189 and 244, is engaged by a pin 262 carried by an arm 263. This arm is swingable about the axle 56 which carries the bow arm 55 and is provided, at its upper part, with pin 155 which engages the slot 154 of the right hand portion of the arm 152 carrying the rocking lever (FIGURE 26).

By means of a pin 264 (FIGURE 11), the arm 263 is articulated to a bar 265 which due to the angular displacement of the arm 263 about the axle 56, is movable in its longitudinal direction. The right-hand part of the bar carries a pin 266, which slides in a V-shaped recess in a vertical frame wall. The two branch slots of the recess are designated by 267 and 268. Upon the longitudinal displacement of the bar, the pin 266 is normally moved into the slot designated by 267. At the left-hand end portion of the bar 265 there is provided a pin 269, which is connected, by means of a spring 270, to a fixed pin 271. The spring 270 tends to turn the bar 265 in a clockwise direction about the pin 264 so that the pin 266 is moved towards the lower edge of the slot 267. Said pin 266 projects forward, and the bar is disposed behind the slot 267, 268.

When the arm 142 (FIGURE 17) is moved in a clockwise direction downwardly into the negative position, a nose 272 connected to the arm passes into engagement with the pin 269 and carries the adjacent part of the bar 265 downwardly, whereby the right-hand part of the bar is swung upwardly so that the pin 266 on the last-mentioned part may be forced into engagement with the slot 268. At the right-hand part of the bar there is provided a shank arm 273 which, depending upon the different positions of the bar 265 corresponding to the slots 267 and 268, passes into engagement with one of two operating arms 274 and 275, which arms are in this way adjusted through the displacement of the bar to the left in its longitudinal direction from the shown position. Due to said displacement of the operating arms 274 and 275 transmission clutches for effecting respectively positive and negative setting-up in the adding machine are controlled.

Mode of Operation

By depressing one of the multiplication keys 10, there are obtained by virtue of the slots 22, 23 and 24 of the disks 21 (FIGS. 3 and 4) operating movements for the value and the setting-up sign of the in-put digit together with an adjustment of the starting mechanism for starting the machine.

By the assistance of the mechanism disclosed in FIG. 5, the digit value or its complementary number is transmitted to the power driven registering and setting-up 30 device shown in FIG. 7, and wherein the digit is registered by the driving arm system 100 (FIG. 23) driven under the control of the axle clutch mechanism as in FIG. 21.

The registering arm 51 is adjusted angularly in a clockwise direction in consideration of the necessity of an additional entry operation in the machine. This is accomplished by the slide 110 (FIGS. 19 and 23) displaceably mounted on the driving arm system 100 and with the slide 110 being moved into operative position when the figure character is altered by change of sign or upon a change from one digit group 0 to 5 to the other digit group 6 to 9, or vice versa. The complementary numbers of the digits of the last named group consist of the negative numbers "-3," "-2," "-1" and "0," respectively, whereby, by means of the rod 31 (FIG. 4), the arm 142, 158 (FIG. 17) is moved into the negative position 40 for the digits 6 to 9.

The additional entry operation is achieved by swinging the lever 51 (FIG. 7) down through an angle corresponding to the pitch of the comb 50 beyond that angular adjustment which corresponds to the registered digit value. Thus, the actuator performs an additional operation for both addition and subtraction.

The oscillating arm system 126 shown in FIG. 24 performs a controlling function. The arm 125 associated with the system steers, by means of the slot 173 and the pin 179, the rocking lever 180 (FIG. 15) in such a manner that the freeing of the circuit closing lever 186 by pawl 183 takes place after a delay. When the lever 186 assumes its right position, namely the position shown in FIG. 15, the motor circuit is opened.

Simultaneously, the arm 125 (FIG. 24) releases the pawl 121 for the actuating arm 116 of the slide 110 and such is shown in FIGS. 19 and 23. Furthermore, the arm system 126 serves as a stopping arm system by virtue of the cooperation of its arm 162 (FIG. 24) with the pawl 164. The arm 168 of this system moves the arm 92 into freeing position whereby the driven part of the axle clutch is caused to execute one revolution. The fourth arm 170 of the arm system effects a tabulating stop (not shown) into operative position when an additional entry operation has to be performed upon a change from negative to positive feeding.

The driving arm system 100 (FIG. 23) serves the following purposes. The arm system contains the arms 102 provided with the curved arms 106, 103, 104 and 105.

Upon the stroke of the driving arm system in the counter-clockwise direction, the arm 105 together with the slide 110, effects the registration of the in-put digit value by bringing down the toothed sector 60 (FIG. 7) a fixed number of teeth.

The arm 102, 106 delivers the moving force to the impulse transmission required for an additional entry operation.

The arm 158, which by means of the pin 159 (FIG. 17) actuates the oscillating arm system 126 (FIG. 24) and carries the pin 167 actuated by the arm 106 when the rod 31 by means of the key 10 has been displaced from the positive to the negative position, namely when the arm system 142, 150 assumes its right position (FIG. 17).

Upon a movement in the counter-clockwise direction, the arm 103, by means of its pin 230 frees the arm system 126 from the pawl 164 and upon a movement in the clockwise direction, it returns the slide actuating arm system 116, 123 and thereby the slide 110 to the initial position.

The arm 107 which forms a prolongation of the arm 104 adjusts angularly the bow arm 55 to engage the registration arm 51 with the arm 42 controlled by the rod 25, which latter part functions to indicate the digit value.

The operation is further explained with reference to a calculating example:

A×2685

The multiplicand "A" is first set up on the keyboard 3 beginning with the digit of highest denomination, and then the operator beginning with the lowest digit, will set up the multiplier setting mechanism keys 10. The multiplier key denoted "5" is next depressed.

By depressing the key "5," the parts are carried into the position of FIG. 3 as indicated by the dotted lines. The rod 25 is, however, brought to the position "5" instead of the "1" position. The arm 30 (FIG. 5) carrying the rod 25 and the arm 42, which is moved by means of the arm 30 are brought to a "5" position and the link pin 45 is located at the upper side of the uppermost tooth 48 of the arm 51 (FIG. 7), i.e. at the tooth gap designated by 49 of the comb 50. When the machine is started, the link pin 45 is introduced into engagement with the tooth gap 49 by means of the bow 55 as shown in FIG. 9.

The rod 31 and thus the arms 130 and 142 (FIG. 17) are maintained in the left position corresponding to position of positive calculation.

The rod 34 is moved into the starting position and the arm 69, 70 to a corresponding position indicated by dotted lines in FIG. 13.

The sign indicating bar 265 (FIG. 11) will be moved from its initial position shown to the left under the action of the arm 263 which in turn, by means of the pin 262 and the slit 261 of the arm 242, is swung clockwise because the stroke of the arm 242 corresponds to the stroke of the lever 51 (FIG. 7) as the arm 242 is connected with the lever 51 by means of the slit 241 and pin 240. Since, in the initial position of the bar 265, the arm 142 (FIG. 17) remains in its initial (positive) position, the pin 269 of the bar 265 is at a distance from the nose 272 of the arm 142. Hence, the stroke of the sign bar occurs under the action of the spring 270 and the shank arm 273 will actuate the operating arm 274. Such arm is arranged to maintain the state control pitman 356 (FIG. 3 of Patent No. 2,397,745) in its lower position or shift the pitman 356 from its upper or subtract position to its lower or adding position.

As above described, the starting arm 69, 70 is moved into its starting position so that the arm, by means of the abutting edge 72, displaces the locking lever 92, 94 (FIG. 13) into its freeing position whereby the axle clutch 84, 173 (FIGS. 21 and 22) is moved into operating position. Thus, the driving part 84, 85 of the axle clutch will rotate the driven part, namely the disk 173. The disk 173 (FIGS. 22 to 25) is provided with the guide slot 172 for

the pin 171 of the driven arm system 100 (FIG. 23). The stroke of the driving arm system is obtained by the assistance of the disk 173.

Simultaneously with the displacement of the starting arm 70 to the left, in which position the arm is locked by means of its pin 224 and the latch 221 (FIG. 23), the upper edge portion 194 of the arm actuates the pin 193 of the branch arm 192 belonging to the circuit closing lever 186 (FIG. 15) so that the lever 186 is swung clockwise into the circuit closing position. Hence, the motor starts and the driving arm system 100 performs its working stroke in a counter-clockwise direction.

Thus, the lever 51 (FIG. 7) coupled together with the arm 42 by means of the link pin 45 is moved downwardly a distance corresponding to five teeth 61 of the sector 60 carried by the registering lever 51.

The pin 240 (FIGS. 7 and 11) of the lever 51 runs during the movement of the lever in the slot 241 of the arm 242. This latter component which is provided with

20 the guide curves 189 and 244 is swung in a counter-clockwise direction and the guide curve 244 displaces the tabulating slide 246 to the right, while at the same time, the guide curve 189 occupies a locking position for the pin 188 and hence for the circuit closing lever 186 whereby such lever is maintained in the circuit closing position until the lever 51, by means of the pin wheel 65 (FIG. 7) is stepped back into its initial position. It will be noted that in the return movement of the lever 51, its pin 240 runs upwardly in the slot 241 of the arm 242 and that the arm 242 is maintained in its operative position as shown by the dotted lines in FIG. 11 until the pin 240 reaches the uppermost portion of the slot 241, i.e. until the last return step of the sector 60 is effected.

30 The arm system 126 (FIG. 24) remains disengaged 35 because the rod 31 and the arm 142 with the branch arm 158 (FIG. 17) remains in the initial position shown by full lines in said figure. Thus, the pin 159 at the end portion of the arm 158 will not be moved against the edges 160 and 161 of the arm 162 pertaining to the arm system 126.

40 During the stroke of the driving arm system 100, the starting arm 70 and hence the key 10 actuated for the digit "5" will be freed due to the fact that the pin 220 of the bow shaped arm 106 (FIG. 23) relating to the driving arm system actuates the latch 221 in a clockwise direction. The starting arm returns into its initial position under spring tension, namely the action of the spring 16 which tends to move the arm 19 upwardly and thus displaces by means of the slot 24, the rod 34 into its initial 45 position. The circuit closing lever 186 is, however, by means of its pin 188 and the guide curve 189 (FIG. 11) locked in the circuit closing (left) position as in FIG. 15.

50 The depressed key "5" can accordingly return to its initial position already after the stroke of the driving arm system 100 in the counter-clockwise direction. The arm system will, by means of the guide slot 172 and the pin 171 cooperating therewith (FIG. 23), immediately return to its initial position indicated by full lines since the disk 173 provided with the slot 172, after one single revolution 55 is disconnected from the driving part 84 of the axle clutch illustrated in FIGS. 21 and 22.

60 Due to the fact that the circuit closing lever 186 is, by means of the curve 189 and its pin 188, maintained in its operative position, the switch 471, 472 in FIG. 2a of Patent No. 2,397,745 is closed and as the machine is driven in synchronism with the stepping wheel 65, the multiplicand "A" is entered positively five times into the calculating mechanism of the adding machine.

65 During the clockwise movement of the driving arm system 100, the pin 212 of the bow arm 55 (FIG. 9) is displaced upwardly into its initial position (FIG. 23) by the aid of the arm 107 and the slot 210 thereof so that the bow arm 55 moves the link pin 45 out of engagement with the comb 50 as in FIGS. 9 and 7, the arm 42 thus being

released and able to return upwardly under spring action to its initial position.

The machine shown in Patent No. 2,397,745 is provided with a mechanism (FIG. 1) able to effect a single denominational step of advance of the pin carriage 305 (page 10, right column, lines 53 to 71). In such a case, the adding machine after the five adding operations is prepared for the entry of the second partial product of the multiplier multiplicand.

If, however, the pin carriage 305 is to be stepped under control of the multiplying device above described, the stepping mechanism 245 to 255 shown in FIG. 11 may be used.

When the arm 242 together with the registering lever 51 are returned to their initial positions, the slide 246 is under spring action, moved to the left and its pin 215 arrives in the path of the lug 214 of the arm 104 included in the driving arm system 100. The pin 215 is actuated by the lug or shoulder 214 when the next multiplier key 10 is depressed so that the slide carrying arm 251 is swung in a clockwise direction about the axle 252. Thus, the lower end of the arm 251 moves the fork 255 to the left.

The fork 255 or its arm 256 (FIG. 12) may be connected with the adding machine key lever 359 in order to effect the denominational step of advance of the pin carriage 305 in the adding machine as in Patent No. 2,397,745.

When the key 10 for the digit "8" is depressed, the pertinent slotted guide disk 21' (FIG. 4) is displaced downwardly, the pin 45 on the arm 42 being moved to that tooth gap 47 on the comb 50 which corresponds to the digit value "1." In this case, all of the three rods 25, 31 and 34 are moved so that also the arm 142 (FIG. 17) is displaced. When the driving arm system 100 (FIG. 23) is started in the manner described above, the arm 142 is, by means of the curved arm 106 which actuates the pin 167 at the upper end of the arm 142, moved into its right-hand position in which the pin 159 (FIG. 17), after having withdrawn the arm 162 of the arm system 126 (FIG. 24) a certain distance, is located below the abutting edge 161 (FIG. 17) on said arm. Hence, the arm system 126 becomes operative whereby the pawl 121 (FIG. 24), by means of the arm 125 and its pin 176 is withdrawn from the arm 116 (FIGS. 23, 29) so that this latter part under spring action displaces the slide 110 (FIG. 23) into operative position (FIG. 19). Therefore, upon starting the driving arm system 100 (FIG. 23), the lever 51 is moved down through an angle equal to two steps, i.e. one step for the digit value "-1" and one step for obtaining an additional feeding operation. These two feedings are negative, which is determined by the sign bar 265 (FIG. 11) after this latter component has engaged the nose 272 (FIG. 17) on the arm 142, which nose adjusts the bar angularly a short distance in a counter-clockwise direction about its pin 264. Consequently, the shank 273 (FIG. 11) of the bar will, during the stroke of the bar to the left which occurs upon the downward movement of the registering lever 51 and by means of the arms 242 and 263 (FIG. 11), the first step, pass into engagement with the operating lever 275 which steers the machine for negative feeding. The arm system 126 is freed from the pawl 164 (FIG. 24) during the stroke of the driving arm system 100 (the arm 103 in FIG. 24) in a counter-clockwise direction. However, when the sector 60 (FIG. 7) has been stepped back the contemplated two steps upwardly, the arm 242 and thus the rocker arm 263 (FIG. 11) return to the initial position whereby the pin 155 of the latter arm moves the arm 152 (FIG. 26) in a counter-clockwise direction into the position shown in full lines in FIG. 26 so that the rocking lever 148 passes into engagement with the pin 156 on the arm 142 (FIG. 17) which by this means is returned to its initial position under impulse transmission to the arm 162 of the arm system 126 by means of the pin 159 (FIG. 17) so that said system is again moved into operative position and is locked by the pawl 164.

The adjustment of the pawl 121 (FIG. 24) to freeing position occurs by the aid of the arm 125, and the arm 116 (FIG. 19) is released so that the slide 110 is again advanced for an additional entry operation. The arm 125 maintains simultaneously the circuit closing lever 186 in operative (left) position because the pin 179 of the rocking lever 180 (FIG. 15) which pin engaging the slot 178 of the arm 125 has been displaced in such a manner that the pawl 183 locks the branch arm 185 of the lever 186. At the same time, the rocking lever 180 is displaced out of the path of the eccentric pin 201 of the disk 200.

Due to the operative position of the arm system 126, the arm 168 (FIG. 24) being in engagement with the pin 96 of the locking lever 92, 94 (FIG. 13), the locking lever has released the control arm 88 for the clutch 84, 173 (FIGS. 21 and 22) and the driving arm system 100 (FIG. 23) performs its operative stroke. At this moment, stepping of the pin carriage of the adding machine to the next higher denominational position occurs through the engagement of the lug 214 (FIG. 23) with the tabulating slide pin 215 (FIG. 11) and thereby moving the arm 251 (FIG. 11) in a clockwise direction, and moving the fork 253 and the tabulated arm 256 (FIG. 12), in case no further figure key 10 is depressed, a positive entry of the multiplicand "A" is obtained since the arm 142 is in an inoperative position (the initial position) and hence the bar 265 (FIG. 11) cooperates with the operating lever 274 (+ lever) for positive feeding. The machine would subsequently stop and the counter of the machine would indicate a product, in which the multiplier represents the number "85."

At an ordinary running speed of the machine, the operator has, however, sufficient time to depress the figure key for the digit "6," i.e. the third figure of the multiplier, counted from the right, before the machine is able to perform the above mentioned positive feeding operation. Under such circumstances, the arm 142 (FIG. 17) remains in the negative position and the arm 42 is swung downwardly into the position in which its pin 45 is located at the fourth tooth gap 47 from below in the comb 50. When the driving arm system 100 (FIG. 23) is started, owing to the upward displacement of the arm 70 (FIG. 13) and hence of the stopping arm 92, three teeth 65 on the sector 60 move downwardly past the pin wheel 61 due to the fact that the slide 110 is in an inoperative position since during the return movement of the preceding calculating operation, the driving arm 103 (FIG. 24) has restored the two arms 116 and 128 (FIG. 19) to the initial position and the arm system 126 (FIG. 24) is in its initial position. The arm 142 retains the sign bar 265 for movement of stroke in the negative position so that three negative feeding operations are obtained. The pin carriage of the adding machine is stepped once again, and the multiplication device is ready for introducing the 1000 digit "2" of the multiplier. However, the arm system 126 is in the position shown in FIG. 24 by means of the dot and dash lines by reason that, upon the return of the registering lever 51 and thus of the arm 263 (FIG. 11), the arm 152 (FIG. 26) having been adjusted angularly in a counter-clockwise direction and hence by means of its rocking lever 148 has thrown back the impulse arm 142. By this action, the slide 110 has been moved into operative position whereby the sector 60 is moved downwardly 2+1 steps by the driving arm system 100. In consequence, of the fact that the impulse arm has been returned to the initial position, the bar 265 (FIG. 11) occupies its positive position whereby three positive feedings are obtained in the adding machine, which is thereafter brought to a stop. Hence, the multiplicand has been added five times in the first decade, has been subtracted two times in the second decade and three times in the third decade and further has been added three times in the fourth decade. Consequently, the multiplier may be signed 3005-320, which is equal to 2685, i.e. the number assumed according to the example.

Upon the depression of the figure key for the digit "0," the rod 25 remains non-influenced so that the pin 45 of the arm 42 is inserted in the appropriate lowest tooth gap 46 of the comb 50. The starting arm 70 is moved into the starting position and the driving arm system 100 performs its movement of stroke, and an accumulated additional feeding operation then is obtained in case such an operation is required because of the preceding calculating operation. If, however, a positive feeding operation has taken place in the next preceding decade, there is performed, upon the depression of the key "0," only tabulation in the adding machine, which is obtained by the assistance of the lug 214 disposed on the curved arm 107, with the lug then passing into engagement with the pin 215 on the tabulating slide 246.

The multiplication key 10 for the digit "9" does not displace the arm 42 and for this reason, the pin 45 remains in the zero "0" position and is inserted in the tooth gap 46 of the comb 50. However, the impulse arm 142 is actuated so that one feeding operation with negative sign is obtained by the assistance of the slide 110. In this situation, the lug 214 does not become operative, since the tabulating slide 246 is withdrawn. Thus, a multiplier consisting of the number "999" causes in the first decade, a single negative feeding of the multiplicand the slide 110 then being moved into inoperative position so that the succeeding two digits only cause tabulation by means of the lug 214 whereupon the accumulated positive entry takes place in the fourth decade.

The invention is not to be confined to any strict conformity with the showings in the drawings but changes or modifications may be made therein so long as such changes or modifications mark no material departure from the spirit and scope of the appended claims.

What I claim is:

1. A calculating machine including means for controlling the repeated registration of a multiplicand, means to enable the machine to perform multiplication by a shortened method, including multiplier keys representing the cardinal digits from "0" to "9," a digital value indicator and a sign indicator for each of the multiplier keys, means operably coupling said indicators to the keys for actuation by said keys, registering means angularly adjustable from a zero position, a multiplier setting mechanism operably connected to and actuated by the digital value indicator and operative for introducing the multiplier digits consecutively into the registering means, a driving system comprising an adjustable driving member adapted to be influenced by the sign indicator, means operably connecting the driving system to the registering means for adjusting said means from the zero position a number of steps corresponding to the registered value and an additional step in case the adjustable driving member has been influenced by the sign indicator, a tooth series operably connected with the registering means, a step wheel controlling the entry of the multiplier into the machine, means to drive the step wheel, means on the step wheel cooperable with said tooth series and stepping said registering means back to the zero position, and means to stop the step wheel when it steps the registering means back to zero.

2. A calculating machine according to claim 1, wherein the digital value indicator and the sign indicator consist

of guide slots formed in a disk which is angularly adjustable and connected with the multiplier key.

3. A calculating machine according to claim 1, wherein the multiplier setting mechanism comprises two spring connected arms swingably mounted on a common axle, one arm of which carries a rod actuated by the digital value indicator and the second arm being provided with a link carrying a pin arranged to engage the registering means after setting of the second arm.

4. A calculating machine according to claim 1, comprising a sign transmitter adjustable into a positive and a negative position and governed by the sign indicator when taking the negative position is actuated by the driving system, a spring lever mechanism releasable by said transmitter under the action of the driving system and arranged to displace the adjustable driving member into active position to obtain an additional entry in the adding machine.

5. A calculating machine including means for controlling the repeated registration of a multiplicand, means to

enable the machine to perform multiplication by a shortened method, including multiplier keys representing the cardinal digits from "0" to "9," means to start the machine, a digital value indicator and a sign indicator for each of the multiplier keys means operably coupling said indicators to the keys for actuation by said keys, registering means angularly adjustable from a zero position, a multiplier setting mechanism operably connected to and actuated by the digital value indicator and operative for introducing the multiplier digits consecutively into the registering means, a driving system comprising an adjustable driving member adapted to be influenced by the sign indicator, means operably connecting the driving system to the registering means for adjusting said means

from the zero position a number of steps corresponding to the registered value and an additional step in case the adjustable driving member has been influenced by the sign indicator, a tooth series operably connected with the registering means, a step wheel controlling the entry of the multiplier into the machine, means to drive the step wheel, means on the step wheel cooperable with said tooth series and stepping said registering means back to the zero position, and means to stop the step wheel when it steps the registering means back to zero.
